UNITED STATES PATENT OFFICE

JOSEPH HARLING TURNER BORLAND, OF KILMARNOCK, SCOTLAND

EMERGENCY SLUICE GATE

Application filed June 15, 1931, Serial No. 544,588, and in Great Britain July 23, 1930.

This invention relates to a portable emergency sluice gate of the type comprising a frame fitted with a series of parallel rollers, and primarily devised for closing the inlet to a discharge culvert or tunnel of a storage dam or the like for the purpose of dewatering the culvert and its permanent control sluice to permit inspection and control of these parts.

In the construction described in the specification of Letters Patent No. 1,797,042, dated 17th March, 1931, the gate frame was composed of upright angle end posts held apart by diagonal bracing bars, and the rollers were made in the form of solid round bars retained in relative position by means of end bearings.

The said bracing bars were fixed to the upstream side only of the frame, so that in effect the end posts constitute a cantilever.

The present invention is designed to obviate any possibility, when the gate is subjected to the water pressure, of the hydraulic forces acting on the outside of the end posts tending to bend them inward against the ends of the rollers and thus setting up frictional resistance to the free rolling motion of the gate.

According to the present invention the rollers are constructed as hollow cylinders with bushed ends penetrated by central axles on which the rollers revolve and which retain the rollers in their relative position and also function as distance pieces between the end posts which they support on their centre line, thus departing from the cantilever form above referred to and obtaining greater strength to resist the external hydraulic pressure load when the gate is in closed position and submerged.

The rigid construction of central support to the end posts obviates any possibility of inward deflection and consequent end friction on the rollers, thus contributing to the freedom of rolling motion of the gate.

A sluice gate constructed in accordance with the invention is illustrated in the accompanying drawings in which Fig. 1 is an elevation looking upstream on the gate, Fig. 2 a half plan half horizontal section, Fig. 3 an elevation at right angles to Fig. 1, Fig. 4 a section on the line 4-4 of Fig. 1, and Figs. 5

and 6 fragmentary detail views drawn to a larger scale.

As shown the rollers 1 are constructed as hollow cylinders penetrated by axles 2 on which the rollers 1 revolve and which retain the rollers in their relative position and also function as distance pieces rigidly interconnecting the end posts 3 of the gate frame, the axles having end portions of reduced diameter fitted to orifices in the end posts so as to present shoulders maintaining clearance between the rollers 1 and the end posts 3 and effectively relieving the rollers of end thrust.

The rollers 1 are equipped at their ends with bushes 4 journalled on bearing sleeves 5 embracing the axles 2.

The stauching members 6 which are disposed parallel to the rollers 1 and which serve to seal the clearances between adjoining rollers 1 are constituted as steel tubes.

The upper ends of the end posts 3 are bridged by means 7 between which are mounted two lifting rope pulleys 8.

What I claim is:—

An emergency sluice gate for the purpose specified comprising a frame having end posts, a series of parallel axles perpendicular to said end posts and forming distance pieces rigidly interconnecting said end posts, a series of closely spaced rollers formed as hollow cylinders journalled on said axles, with clearance between adjoining rollers, said axles presenting shoulders abutting on said end posts, maintaining clearance between said rollers and said end posts, and stauching members parallel to said rollers and serving to seal the clearance between adjoining rollers, said rollers and stauching members forming in effect an uninterrupted closure, said frame, axles, rollers and stauching members constituting a self-contained portable unit.

In testimony whereof I have signed my name to this specification.

JOSEPH HARLING TURNER BORLAND.
